Fig. 4

FIG. 1 is a side elevational view of a skillet or the like embodying our new design, with the opposite side being identical.

FIG. 2 is an end elevational view, the opposite end being identical.

FIG. 3 is a top plan view.

FIG. 4 is an enlarged fragmental view in elevation taken on line 4-4 of FIG. 3.

The characteristic feature of the design resides in the particular ornamentation applied to the outer wall, as shown.

We claim:

The ornamental design for a skillet or the like, as shown and described.
